R. T. JENNEY,
MEANS FOR OPERATING DRIVEN MECHANISMS,
APPLICATION FILED APR. 5, 1915.

1,214,039.

Patented Jan. 30, 1917.

UNITED STATES PATENT OFFICE.

ROBERT T. JENNEY, OF MONTICELLO, IOWA.

MEANS FOR OPERATING DRIVEN MECHANISMS.

1,214,039.

Specification of Letters Patent. Patented Jan. 30, 1917.

Original application filed December 7, 1914, Serial No. 875,860. Divided and this application filed April 5, 1915. Serial No. 19,386.

To all whom it may concern:

Be it known that I, ROBERT T. JENNEY, a citizen of the United States, and a resident of Monticello, in the county of Jones and State of Iowa, have invented a new and useful Means for Operating Driven Mechanisms, of which the following is a specification.

The invention relates to friction-clutches, to the means for operating them, and to mechanism operable by or from the clutch members.

The primary object of the invention is to generally improve the construction and to increase the capacity, utility and efficiency of devices of the same or a similar nature.

Other objects will presently appear. Some of these will be obvious and others will be specifically pointed out.

20 The invention consists, substantially, in the constructions and combinations shown in the accompanying drawings and herein described.

The above noted objects I attain by means, 25 a preferred form of which is illustrated in said drawings, said form being identical with that shown and described in my co-pending application, filed December 7, 1914, No. 875,860, for patent for corn-husker, 30 ensilage-cutter, and silo-filler, of which the present application is a division.

It is to be understood, however, that while I have in the foregoing named application shown the herein described improvements 35 in connection with or embodied in a machine for performing certain operations on corn, the herein described means is applicable to any mechanism with which it may be operatively connected.

40 In the drawings above referred to: Figure 1 is a top plan; Fig. 2, an enlarged sectional detail, partly in elevation; Fig. 3, an enlarged end detail, the pulley 9 removed and the shaft portion 6 shown in section; and 45 Fig. 4, a detail of the yoke.

The exact construction of the preferred form of my improvements will be described in full herein, but I do not intend by describing the details thereof to be understood 50 as limiting my claims in any way or manner thereto, the scope of the invention being pointed out in the claims hereto appended.

Considering the drawings in detail, and referring to each element and, where required, to each part thereof, by a distin-

guishing numeral, uniformly employed, 2—2 indicate frame-bars which, it may be assumed, are parts of any suitable machine.

3 indicates a drive shaft mounted in bearings 4 secured by bolts 5 to said bars 2. One of its end portions is reduced or constructed, as indicated at 6.

7 designates the drive-pulley fixed on and driving said shaft, and 8 designates the drive-belt embracing said pulley and driven from any suitable source of power.

9 indicates a driven pulley constituting one member of a friction-clutch presently more fully described. It is fixed by a key 10 on the constricted portion 6 of the shaft 70 3. The internal and, relatively to the frame, inner face of its rim is beveled or flared, as clearly shown in Fig. 2.

On the reduced portion of the shaft 3 and bearing against the shoulder 11 provided by reducing its end portion 6 is rotatively mounted a pinion 12 which is integral with an elongated sleeve 13 to which is secured by a spline 14 a friction-clutch head 15 the neck of which is provided with an annular 80 groove 16. Friction-shoes 17 having each a beveled and rounded face 18 adapted to conform to the contour of and to frictionally engage the beveled and rounded inner face of the rim of the pulley 9, are secured 85 by bolts 19 and nuts 20 to the head 15.

20—20' indicate slots, one in the outer end portion of each of the arms of the head 15, and are adapted for the reception of the bolts 19, whereby the shoes 17 may be adjusted relatively to the flange of the pulley 9.

21—21 designate adjusting screws, threaded each through and engaging the threads of a boss 22 and adapted to bear against the 95 shoes 17.

23 indicates an expansion spring encircling the sleeve 13 and arranged between the pinion 12 and the terminal of the neck of the head 15.

24 indicates a yoke (Fig. 4) which seats in the groove 16 in the head 15 and is provided with pintles 25 which engage apertures in a shift-collar 26 the extended portion of which constitutes a shift-lever 27.

28 indicates a link hinged at one end to the collar 26 and at its other end to a frame bar 2.

29 designates a bell-crank lever fulcrumed at 30 to the other bar 2.

31 indicates a link crossing the frame 2 and pivotally connected at its ends to the shift lever 27 and bell crank 29.

32 designates a driven shaft mounted in bearings 36 secured by bolts 35 to the frame 5 bars 2.

33 represents a spur gear wheel fixed on said shaft 32, and 34 indicates a sprocket or other wheel fixed on the same shaft. The wheel 34 is merely illustrative, and any 10 other medium for transmitting motion from the shaft 32 may be substituted therefor.

Assume the parts to be in the relative positions shown in Figs. 1 and 2, in which the shoes 17 are in frictional engagement 15 with the beveled concave face of the rim of the pulley or belt-wheel 9 and the wheels 12 and 33 in mesh. In this position the shaft 3 will transmit motion to the belt-wheel 9 (from which a driving-belt may be actuated) and the pinion 12 will drive the spur 33 and thereby the shaft 32 and wheel 34.

In order to stop the rotation of the wheel 9 the operator will throw the lever 29 to the dotted line position indicated in Fig. 1 25 to draw on the link 31 and thereby cause the lever 27 and collar 26 (through the medium of the pins 25) to shift the yoke 24 inwardly, to thereby retract the head 15 and shoes 17 30 in the same direction, overcoming the resistance of the spring 23 and withdrawing said shoes from their frictional engagement with the rim of the wheel 9. The portion 6 of the shaft 3 will revolve freely in the bore 35 of the sleeve 13, and the movement of the pinion 12 will cease, thereby stopping the movement of the wheels 33 and 34 and the shaft 32, and, of course, any mechanism driven thereby.

40 The shoes 17 may be adjusted toward or from the inner face of the rim of the wheel 9 by suitable adjustments of the screws 21, and after such adjustments they may be locked by means of the bolts 19 and nuts 20.

45 By moving the lever 29 but a short distance the shoes 17 will be drawn but slightly from the rim of the wheel 9, and the shoes will then act as a brake. It will be understood, of course, that any other driving means may 50 be substituted for the belt-wheel 9 or the pinion 12, and that other driven mechanism may be substituted for the wheels 33 and 34 and the shaft 32.

Having thus described the nature of the 55 invention and having described its operation, I claim as new the following, namely:

1. In means of the character described, a shaft having a shoulder and a reduced end portion, a pinion having an elongated sleeve, 60 mounted on said reduced portion and the pinion lying against said shoulder, a friction-clutch head splined to said sleeve, friction-shoes carried by said head, a friction-clutch member adapted for engagement by 65 said shoes, and means for holding said shoes

normally in engagement with said friction-clutch member.

2. In means of the character described, a shaft having a shoulder and a reduced end portion, a pinion having an elongated sleeve, 70 mounted on said reduced portion and the pinion lying against said shoulder, a friction-clutch head splined to said sleeve, friction-shoes carried by said head, a friction-clutch member adapted for engagement by 75 said shoes, and a spring interposed between said pinion and head, for holding said shoes normally in engagement with said friction-clutch member.

3. In means of the character described, a 80 drive-shaft, a pinion having an elongated sleeve, mounted and held from longitudinal movement thereon, a friction-clutch head splined to said sleeve, friction-shoes carried by said head, a friction-clutch member 85 adapted for engagement by said shoes, and means for holding said shoes normally in engagement with said friction-clutch member.

4. In means of the character described, a drive-shaft, a pinion having an elongated 90 sleeve, mounted and held from longitudinal movement thereon, a friction-clutch member slidably mounted on said sleeve, friction-shoes carried by said member, a friction-clutch member adapted for engagement by 95 said shoes, means for holding said shoes normally in engagement with said friction-clutch member, and means for moving the first recited clutch-member and thereby disengaging said shoes from said head. 100

5. In means of the character described, a drive-shaft, a pinion having an elongated sleeve, mounted and held from longitudinal 105 movement thereon, a friction-clutch head splined to said sleeve, friction-shoes 110 carried by said head, a friction-clutch member adapted for engagement by said shoes, means for holding said shoes in engagement with said friction-clutch member, and means for adjusting said shoes on said head and relatively to said friction-clutch member. 115

6. In means of the character described, a drive-shaft, a pinion having a sleeve, mounted and held from longitudinal movement 115 thereon, a friction-clutch head splined to said sleeve, friction-shoes carried by said head, a friction-clutch member adapted for engagement by said shoes, and a spring interposed between said pinion and head and adapted to hold said shoes in engagement 120 with said friction-clutch member.

7. In means of the nature described, a drive-shaft, a pinion having a sleeve, mounted and held from longitudinal movement thereon, a friction-clutch head splined to 125 said sleeve, said head provided with lugs and with slots, bolts slidably seated one in each of said slots, friction-shoes, each secured to said head by one of said bolts, a nut engaging each bolt, whereby the shoes may 130

be locked to said head, screws threaded one through each of said lugs and adapted to force said shoes outwardly, and a friction-clutch member adapted for engagement by said shoes.

5. In means of the nature described, a drive-shaft, a pinion having a sleeve, mounted and held from longitudinal movement thereon, a friction-clutch head splined to said sleeve and provided with lugs and with slots, bolts slidably seated one in each of said slots, friction shoes, each secured to said head by one of said bolts, a nut engaging each bolt, for locking the shoes to said head, 10 screws threaded one through each of said lugs and adapted to force said shoes outward, a friction-clutch member adapted for engagement by said shoes, and means for holding said shoes in engagement with the 15 last recited element.

9. In a friction-clutch, a driving-shaft, a pinion rotatable thereon and provided with a sleeve, said sleeve and pinion held from movement longitudinally of said shaft, 20 a friction-clutch head slidably mounted on said sleeve, friction-shoes carried thereby, a friction-clutch member fixed on said shaft and adapted for frictional engagement by said shoes, and a spring encircling said shaft 25 and adapted normally to engage and hold said head in frictional contact with said friction-clutch member.

10. In a friction-clutch, a driving-shaft, a pinion rotatably mounted thereon and having a sleeve extension, a friction-clutch head having a neck provided with a groove, a yoke seated in said groove, a shoe carried by 35 said head, a spring encircling said sleeve and adapted to normally force said head outward, means for moving said head inward, and a friction-clutch member normally engaged by said shoes.

11. In a friction-clutch, a driving-shaft, a pinion rotatably mounted thereon and having a sleeve extension, a friction-clutch head having a neck provided with a groove, a yoke seated in said groove, a shoe carried by 45 said head, a spring encircling said sleeve and adapted to normally force said head outward, means for moving said head inward, a friction-clutch member normally engaged by said shoes, and mechanism driven by said pinion when the friction-clutch members are engaged, the movement of the 50 pinion ceasing when said members are disengaged.

12. In combination, a pulley constituting one member of a friction-clutch, friction-shoes constituting the other member thereof, 55 said shoes normally engaged with said pulley, a head to which said shoes are secured, a shaft on which said pulley is fixed and relatively to which said head is slidably mounted, a pinion rotated by said head, and mechanism driven from said pinion.

13. In combination, a pulley constituting one member of a friction-clutch, friction-shoes constituting another member thereof, 60 said shoes normally engaged with said pulley, a head to which said shoes are adjustably secured, a shaft on which said pulley is fixed and relatively to which said head is slidably mounted, a pinion rotated by said head, means for slidably engaging it with said head, a shaft on which said pulley is 65 fixed and relatively to which said head is slidably mounted, and a shaft driven from said pinion.

14. In combination, a drive-shaft, a pulley fixed thereon, friction-shoes adapted for engagement with said pulley, a head to which they are removably secured, a sleeved pinion on which said head is slidably mounted, means for preventing rotation of said head relative to said pinion, means for moving 80 said head longitudinally on the pinion-sleeve, for throwing said shoes out of engagement with said pulley, means for throwing and holding the shoes in engagement with the pulley, and mechanism operable 85 by said pinion only when the shoes and pulley are engaged.

15. In combination, a shaft, a belt-wheel or pulley fixed thereon, a pinion rotatable on said shaft, friction shoes movable longitudinally relative to said shaft, means for throwing said shoes into frictional engagement with said pulley, manually actuatable means for throwing said shoes out of said engagement, and mechanism operable from 95 said pinion only when the clutch-members are engaged.

16. In combination, a shaft, an integral sleeve and pinion mounted thereon, a pulley fixed on said shaft, a head slidably mounted 100 on said sleeve, friction-shoes carried by said head, a spring interposed between said pinion and head, to bring the shoes into frictional engagement with said pulley, manually actuatable means for moving said head 105 to move said shoes out of engagement with said pulley, and mechanism driven from said head only when the clutch-members are engaged.

17. In means of the character described, a 110 frame, a shaft mounted thereon, means for driving it, a pulley fixed on said shaft, a sleeve, a head slidably mounted on said sleeve, friction-shoes carried by said head, a spring interposed between said pulley and 115 head whereby said shoes are normally held in engagement with said pulley, means including a link crossing said frame, for moving said head to move said shoes out of engagement with said pulley, and mechanism 120 driven by said pinion only when the clutch members are engaged.

18. In a machine, a drive-shaft, a sheave fixed thereon, friction-shoes, a head to which they are secured, a pinion having a sleeve 125

on which said head is slidably mounted, means for preventing rotation of said head relatively to said pinion, means for moving the head longitudinally on the pinion-sleeve, for disengaging the shoes from the sheave, means for holding the shoes in engagement with the sheave, and mechanism operable

from said pinion only when the shoes are engaged with the sheave.

In testimony whereof I hereto affix my name, at Monticello, Iowa, this 30th day of March, 1915.

ROBERT T. JENNEY.
